CLAIM

The ornamental design for a dual tracking speaker camera, as shown and described.

DESCRIPTION

FIG. 1 is a front perspective view of a dual tracking speaker camera;

FIG. 2 is a front elevation view thereof;

FIG. 3 is a top plan view thereof;

FIG. 4 is a right side elevation view thereof;

FIG. 5 is a left side elevation view thereof;

FIG. 6 is a bottom plan view thereof; and,

FIG. 7 is a rear elevation view thereof.

The broken lines in the figures are for the purpose of illustrating portions of the dual tracking speaker camera, which form no part of the claimed design.

In FIG. 7, everything seen inside the broken lines forming the outer perimeter of the two circular elements of the design forms no part of the claimed design.

1 Claim, 7 Drawing Sheets
